INSTALLATION BRACKET FOR VENETIAN BLINDS

Harry S. Rosenbaum, Baltimore, Md.

Application October 5, 1949, Serial No. 119,684

3 Claims. (Cl. 248—262)

1

This application relates to installation brackets for supporting Venetian blinds. It particularly relates to brackets for supporting blinds having head rails in the form of U-shaped channels in which the operating parts of a Venetian blind, such as tilters, rollers, tilters, cord locks, etc., are contained and concealed. Such a head rail is shown in my copending application Serial No. 22,622, filed April 22, 1948, now Patent No. 2,620,866.

Brackets for supporting head rails such as shown in my application above referred to have heretofore been in the form of rectangular sheet metal boxes having one side open through which the head rail channel extends, the ends of the channel resting on the bottom of the boxes. The front of at least one of the brackets is pivoted to open and close the bracket so that the blind can be placed in the brackets after the brackets have been secured in position. The blind can also be taken down without removing the brackets.

Since the brackets support the whole Venetian blind, they are subjected to an appreciable weight particularly if the blind is used in a window of more than average height. In addition the brackets are frequently subjected to sudden strong forces when the blinds are raised or lowered or the slats are tilted. Persons operating Venetian blinds frequently give the operating cords rather strenuous pulls generally at an angle from the vertical with the result that they tend to pull the blind not only downwardly but also outwardly from the window. Instances have been known in which the force has been sufficient to spring open the front of the supporting bracket and the entire blind has fallen from the brackets. It is obviously important, therefore, that the bracket front be held vertically in the bracket as securely as possible. At the same time, however, the front should be readily released so that the entire blind can be taken down for various purposes, such as cleaning.

I have invented an installation bracket in which the front may be locked in position and which cannot be opened by a pull on the operating cords of the blind regardless of the angle at which the cords are pulled. At the same time the front can be easily released whenever the blind is to be taken down.

In the accompanying drawings I have illustrated a present preferred embodiment of my invention in which

Figure 1 is an isometric view of a Venetian 55 slot 24 is increased in width adjacent its end to

2

blind supported in a window frame by two brackets embodying my invention;

Figure 2 is a side elevation of the bracket looking in the direction of the arrows A—A in Figure 1 and showing the front of the bracket in the closed position;

Figure 3 is a view similar to the view shown in Figure 2 but with the front open;

Figure 4 is a plan view of the bracket shown in Figure 2 with the front closed;

Figure 5 is a bottom view with the front closed; and

Figure 6 is a bottom view similar to Figure 5 but with the front open.

15 Figure 1 shows a Venetian blind supported by brackets embodying my invention. The brackets designated generally by the reference numbers 6 and 7 are held by screws 8 to a permanent support such as a window frame, a portion of which is designated in the drawings by the reference number 9. The blind has a head rail which is in the form of a U-shaped channel 10, the ends of which rest in the brackets 6 and 7. The head rail supports and conceals the operating parts of 20 the blind such as a tilt roller, tilt, cord lock, pulleys, etc., only a tilt roller 11 being shown in Figure 1. The roller 11 supports the usual tapes 12 which carry the blind slats 13.

25 A bracket embodying my invention is shown 30 more in detail in Figures 2 to 6, inclusive. It comprises a generally rectangular sheet metal box having a top 14, a bottom 15, a back 16, a front 17 and one side 18. The rear wall 16 may have a slotted indented portion 19 such as is 35 described and claimed in my copending application Serial No. 766,976, filed August 7, 1947. As shown in the drawings, the front 17 is in the form of an angle member, one flange 20 of which lies parallel to the channel 10 of the head 40 rail and is shaped to have the same sectional contour as the channel. The other flange 21 of the cover extends at right angles to the flange 20 and carries means for securing the cover in a vertical position as will be hereinafter described. The front is pivoted to the side 18 of the bracket 45 adjacent its upper end by a rivet 22 which passes through the side 18 and the flange 21.

The flange 21 is slotted so as to form a tongue 23 which also extends beyond the end of the flange. The bottom 15 has a slot 24 formed therein at the corner formed by it and the side 18 and extending inwardly from the front edge of the bottom for a distance at least equal to the width of the flange 21 of the front. The 50 slot 24 is increased in width adjacent its end to

form a lateral recess 25. The tongue 23 of the front is bent inwardly away from the side 18 as shown in Figure 6 so that when the cover is closed it springs into the recess 25 of slot 24. As is apparent from the drawings, so long as the tongue 23 is in the recess 25 the front of the bracket cannot be opened. After the brackets and head rails have been installed, it occasionally becomes necessary to take the blind down. This can readily be done by pressing the tongue 23 until it contacts the side 18 and then pivoting the front 17 outwardly and upwardly.

When the blinds are installed a small clearance is left between the ends of the head rail 10 and the sides 18 of the brackets. To prevent the head rails from sliding endwise in one direction such as to press against one of the tongues 23 and thus release the front of a bracket, a small lug 26 is stamped out of the bottom 15 of the bracket. This lug is spaced from the end wall 18 at least as far as the tongue 23 when it is in the recess 25. If a head rail should slide endwise the lug 26 will engage the bottom of the U-shaped head rail and prevent further movement of the rail towards the tongue 23.

From the foregoing description it is apparent that I have invented an installation bracket for Venetian blinds which provides a secure support for the head rail, against not only the normal weight of the blind but also strong sudden pulls by persons operating the blind. The bracket, however, can readily be opened whenever it is desired to take down the blind. Moreover, the bracket can be manufactured at low cost by stamping from sheet metal.

While I have described a present preferred embodiment of my invention, it is to be understood that it may be otherwise embodied within the scope of the appended claims.

I claim:

1. An installation bracket for a Venetian blind comprising a rectangular box open at one side and adapted to be secured to a fixed support for the blind, the front of said box being pivoted to the box adjacent its upper end and having a tongue adjacent its lower end, a slot in the bottom of the box extending from a side of the box and parallel to the front of the box, said tongue being adapted to spring into said slot when the front is closed, said box also having a lug extending upwardly from the bottom of the box, the lug being spaced inwardly from the

side of the box at least as far as said tongue when it springs into said slot, thereby preventing movement of a headrail within the box against the tongue.

5 2. An installation bracket for a Venetian blind having a head rail, said bracket comprising a rectangular box open at one side and adapted to be secured to a fixed support for the blind, the front of said box being in the form of an angle member, one flange of the angle extending parallel to the head rail of the blind to be supported in the bracket and the other flange being at right angles thereto, the latter flange being pivoted to the box adjacent its upper end, a slot in the bottom of the box extending inwardly from the front edge and then in a direction parallel to the front of the box, a tongue integral with the pivoted flange and extending beyond the bottom of the box and on the pivoted flange adapted to move in a direction parallel to the front of the box into said slot.

3. An installation bracket for a Venetian blind having a head rail, said bracket comprising a stamped metal rectangular box open at one side and adapted to be secured to a fixed support for the blind, the front of said box being in the form of a stamped metal angle member, one flange of the angle extending parallel to the head rail of the blind to be supported, the other flange extending at right angles thereto and being pivoted to the box adjacent its upper end, the bottom of said box having a recess extending from adjacent one side of the box in a direction parallel to the front of the box, a tongue integral with the pivoted flange and extending beyond the bottom of the box and being bent inwardly and parallel to the front of the box whereby when the front is closed the tongue springs into the recess.
